CLAIM

The ornamental design for an electrical connector as shown and described.

DESCRIPTION

FIG. 1 is a top front perspective view of an electrical connector;

FIG. 2 is a bottom front perspective view of the electrical connector of FIG. 1;

FIG. 3 is an elevated front view of the electrical connector of FIG. 1;

FIG. 4 is an elevated back view of the electrical connector of FIG. 1;

FIG. 5 is an elevated left side view of the electrical connector of FIG. 1;

FIG. 6 is an elevated right side view of the electrical connector of FIG. 1;

FIG. 7 is a top plan view of the electrical connector of FIG. 1; and,

FIG. 8 is a bottom plan view of the electrical connector of FIG. 1.

The broken lines in the drawings depict portions of the electrical connector that form no part of the claimed design. The shade lines in the figures show contour and not surface ornamentation.
